UNITED STATES PATENT OFFICE.

HUGO L. HILLER, OF NEW YORK, N. Y.

LACING-BLANK.

SPECIFICATION forming part of Letters Patent No. 659,849, dated October 16, 1900.

Application filed November 28, 1899. Serial No. 738,521. (No model.)

To all whom it may concern:

Be it known that I, HUGO L. HILLER, a citizen of the United States, and a resident of New York, borough of Manhattan, State of New York, have invented a new and useful Improvement in Lacing-Banks, of which the following is a specification.

My invention relates to an improvement in blanks for lacings, such as shoe or corset lacings, in which the blank is wound for a portion of its length intermediate its ends by a suitable winding-thread, so as to form a lacing tip or tips when the blank is severed.

One object of my invention is to provide a wound portion, as above described, which will be prevented from unwinding when it is severed intermediate its ends.

A further object of my invention is to provide a lacing-tip of the above character, so as to do entirely away with the use of a metallic tip of any kind, the said thread-wound tip being composed of a thread of substantially the same color or of another color, as may be desired.

A practical embodiment of my invention is represented in the accompanying drawings, in which—

Figure 1 represents a lacing-blank, showing a lock-thread-wound portion intermediate its ends before the said portion is severed to form a pair of lacing-tips, the said view also representing a completed lacing-tip at one end of the blank. Fig. 2 is a transverse section through the wound portion of the blank.

Fig. 3 is an enlarged detail view showing the manner of forming the locked wind, so as to prevent the unwinding of the thread when the wound portion is severed. Fig. 4 represents a view of a lacing-blank, showing another way of locking the wound portions thereof, which consists in stitching a continuously-wound thread; and Fig. 5 is a transverse section through the wound portion of the blank shown in Fig. 4.

The lacing-blank is denoted by A, and it may consist of a ribbon or cord, either braided or woven and of any suitable width or size and color.

The lacing-blank is preferably a continuous ribbon from which are formed a plurality of completed lacings for use either for shoes,

corsets, or other purposes for which such lacings would be useful.

The lacing-blank A is wound very tightly for a portion of its length intermediate its ends by a thread B, which thread may be of a color to correspond with the color of the lacing-blank or of another color, if so desired, so as to form a contrast to the body of the lacing when the lacing is completed. This thread is wound so tightly around the blank as to form a very rigid portion. The wound portion of the blank is preferably severed at a point intermediate its ends to form one lacing-tip upon the end of the completed lacing and another lacing-tip upon one end of the blank.

The thread-wound-tip portion of the blank may be locked in different ways to prevent the thread from unwinding when it is severed. In Figs. 1 and 3 I have shown the thread locked against unwinding by looping the thread upon the blank by means of a succession of half-hitches, and in Fig. 4 I have shown the thread as being continuously wound around the blank for the required distance and the thread held against unwinding by a lock-thread C, stitched through the thread and blank. When the thread is applied to the blank by a succession of half-hitches, it may be done by hand; but in practice I employ a machine which applies the half-hitches while the blank is held distended, the ridge formed at the point where one part of the thread passes under a preceding portion, as shown in Fig. 3, naturally assuming a spiral form as the successive turns of the thread are laid in close juxtaposition. The particular machine which I employ to form the half-hitches during the winding forms no part of my present invention, the subject-matter of the present invention being limited to the product. Both of these devices for preventing the unwinding of the thread-wound portion when severed will not permit a thread to unravel more than one of its winds.

The completed lacing with its ends provided with thread-wound tips presents a far neater appearance than the old form of wire or metal tips. The thread-wound tips will keep their color, will not come off, and will not become rusty or discolored. The thread-

wound tips also produce very rigid ends to the lacing, permitting it to be readily laced through eyelets.

To render the thread-wound tips of the lac-
5 ing even stiffer, they may be immersed in a
stiffening liquid—such, for instance, as shell-
lac—if so desired.

While I have shown two ways of locking
the thread against unwinding, it is to be un-
derstood that there may be a number of other
ways of so doing, and it is also to be under-
stood that the tips may be made longer or
shorter and that other changes might be re-
sorted to in the construction of the same.
15 Hence I do not wish to limit myself strictly
to the structure herein set forth; but

What I claim is—

1. A lacing-blank having intermediate its
ends, a thread-wound portion, the winds of
20 the thread being locked to prevent the un-
winding of the thread-wound portion and

forming, when severed, lacing-tips, substan-
tially as set forth.

2. A lacing-blank having intermediate its
ends, a thread-wound portion adapted, when 25
severed, to form lacing-tips, the said thread-
wound portion comprising a series of half-
hitches for locking the thread against un-
winding when the wound portion is severed,
substantially as set forth.

3. A lacing having thread-wound tips pro-
vided with means for preventing unwinding
of the thread, substantially as set forth.

In testimony that I claim the foregoing as
my invention I have signed my name, in pres-
ence of two witnesses, this 16th day of No-
vember, 1899.

HUGO L. HILLER.
